UNITED STATES PATENT OFFICE.

CHARLES L. PEIRCE, JR., OF PITTSBURGH, PENNSYLVANIA, ASSIGNOR OF ONE-HALF TO HUBBARD AND COMPANY, OF PITTSBURGH, PENNSYLVANIA, A CORPORATION OF PENNSYLVANIA.

REMOVAL OF EXCESS COATING MATERIAL FROM COATED ARTICLES.

Application filed March 11, 1920. Serial No. 365,001.

To all whom it may concern:

Be it known that I, CHARLES L. PEIRCE, Jr., a citizen of the United States, and a resident of Pittsburgh, in the county of Allegheny and State of Pennsylvania, have made a new and useful Invention in Removal of Excess Coating Material from Coated Articles, of which the following is a specification.

10 This invention relates to the removal of excess coating material from coated articles while the coating material is in a liquid state.

An object of the invention is the production of a simple, effective and commercial method of removing excess coating material from bulky articles, such as rods, pipes or plates, which have been coated by the application of liquid coating material.

20 A further object is to produce a simple and effective method for removing excess galvanizing material from bulky articles, which have been coated by the hot galvanizing process.

25 These and other objects, which will be made more apparent throughout the further description of the invention, are attained by means of the method herein described as an embodiment of the invention.

30 In the drawings accompanying and forming a part hereof, Figure 1 is an end elevation of apparatus which may be employed in carrying out my invention. Figure 2 is a side elevation of the apparatus shown in Figure 1, portions being shown in section and broken away for convenience of illustration.

35 It is customary in galvanizing articles by the hot dip galvanizing process to submerge them in a bath of molten galvanizing material. Where the articles are bulky such as plates, rods or pipes, any suitable means may be employed for so subjecting them to the bath that the entire surface of each article is subjected to the coating actions of the bath. It will be apparent that such articles are subjected to and do take up heat from the bath and that excess coating material adhering to them remains in a molten condition for an appreciable time after the article has been subjected to the bath. The period of time during which the excess material remains in the molten state depends some-

what upon the size of the article, the length of time it is subjected to the molten bath, 55 the temperature of the bath and the atmospheric temperature. This, however, is only incident to my invention, since with my invention, the removal of the excess material is accomplished immediately after the 60 coated articles are withdrawn from the bath, while they are still hot, and while the excess material is still in a molten state. The articles removed from the bath of molten metal may be suspended over the 65 bath of molten metal in such a way that they are capable of swinging freely at least within certain limits. They are then subjected to a hammer-like blow of sufficient velocity and force to cause them to swing with a high 70 or projectile-like velocity against a stationary or substantially rigid abutment or anvil, so arranged in the path of the articles that it abruptly or instantaneously checks the motion imparted to them by the blow. 75

In the drawings I have illustrated apparatus which may be employed in carrying out the invention. As illustrated, a receptacle 3 is provided at one edge with a substantially rigid upright 4 forming a support for 80 an abutment or anvil 5, which is suitably mounted thereon and as shown extends horizontally and is located some distance above the upper edge of the receptacle. A swinging hammer or striker 6 is so located with 85 relation to the abutment that it is capable of being moved at a high velocity into contact with the articles, such as rods A suspended between the striker and the abutment. 90

As shown in the drawings, the striker consists of a long cylindrical weight rigidly secured to two pivotally mounted rods 7 to which an impelling force may be imparted by any suitable means. In the drawings, 95 one rod 7 is shown provided with an integrally formed power arm 8 which extends substantially at right angles to the rod and is adapted to be actuated by a foot lever 9 through the agency of a link 10. Each of the rods 7 is shown provided with a counter-balancing weight 11 and each is provided with several mounted apertures 12 for the striker, so that the striker may be moved to different longitudinal positions with relation to the rods. The rods are of such 105

length that their fulcrum points are located well above the abutment 5, and they are of such length with relation to the power arm 8, that the motion imparted to the power arm is greatly magnified both from the standpoint of velocity and intensity, in so far as the striker 6 is concerned. In other words, the position of the striker is such that a relatively slow motion imparted to the arm 8 will cause the striker to move with a high velocity and with great force against the suspended articles from which the excess coating material is to be removed. As shown in the drawings, each rod 7 is rigidly mounted on a shaft 13 and the shaft is journaled in brackets 14, which may be secured to the ceiling or roof structure of the building in which the receptacle 3 is located. It will be apparent that a single counter-weight may replace the two counter-weights 11 shown in Figure 2 and that it may be mounted on the shaft 13 independently of the rods.

By employing a relatively long striker 6 and a relatively long abutment 5, the operating mechanism of the striker may be so located with relation to the receptacle that it will not interfere with nor prevent the use of suitable suspending devices for the articles acted upon. For example, such articles may be suspended by means of a crane or merely by means of a pulley 17 and chain 18.

As shown in the drawings, I preferably employed a rack 20 capable of receiving a number of rods A and of suspending them in the desired position. The rack shown consists of two flat steel bars 21 spaced by means of pipe sections 22 and provided with supporting arms 23 which may be engaged by a supporting hook secured to the chain or cable 18. The cable 18 passes over the pulley 17 and its free end may be secured to any rigid support in the usual manner.

As shown in the drawings, the upright 4 is provided with several apertures 15 which may be employed in mounting the abutment in different positions along it. It is also provided with an imperforate plate 16 spaced away from the abutment and adapted to form a shield for catching excess coating material removed from articles striking the abutment. It may also be so located that the material thus removed will drop into the receptacle 3.

In carrying out my invention, the freshly coated articles are suspended between the abutment and the striker while hot and while the coating material is still in a molten state. The striker is then moved against the article or articles so suspended with sufficient velocity and with sufficient force to strike the articles a projectile like blow of such intensity that the article or articles are projected with a high velocity against

the abutment. Under such conditions, the impact to which the articles are subjected causes them to shed the excess coating material. Such excess material as remains on the article at the time of impact with the abutment is shed from the article by the force of that impact.

It will be apparent that the weight and velocity of the striker and its position with relation to the suspended articles must be such that it is capable of abruptly accelerating the articles at the time of impact with them, so that the articles are caused to swing at a high velocity. The force imparted must also be so proportioned that it will instantaneously accomplish the result above described and will do more than set up vibrations or local displacement of the articles. In carrying out my invention I have found that under certain conditions, the abutment may be dispensed with, since the hammer blow of the striker is sufficient to remove excess material. The use of the abutment, however, is advantageous in that it insures a thorough removal of the excess material and, by limiting the swing of the articles struck by the striker, simplifies the procedure after the excess material has been removed. After the articles have been treated as above described, they are removed from their suspended position in any suitable way.

While I have described but one method embodying my invention and while I have illustrated and described but one form of apparatus for carrying out the same, it will be apparent that various changes, additions and modifications may be made both in the method and in the apparatus without departing from the spirit and scope of the invention as set forth by the appended claims.

What I claim is:

1. The method of removing excess coating material from an article coated with liquid coating material, which consists in suspending the coated article, so that it is capable of swinging, in striking it a blow of such force that the suspended article is projected at a high velocity against a substantially rigid abutment.

2. The method of removing excess galvanizing material from an article coated by the hot dip process, which consists in suspending the galvanized article, and subjecting it while hot and while the excess material is in a molten state, to a projectile like blow of sufficient force and magnitude to project the suspended body against an abutment.

3. An apparatus for removing excess coating material from an article coated with a liquid coating comprising an abutment, a striker secured to a long pivotally mounted rod, means for suspending a coated article between the abutment and the striker and

means for swinging the striker against the suspended article with a projectile like velocity.

4. The method of removing excess galvanizing material from an article coated by the hot dip process, which consists in suspending the galvanized article, and subjecting it while hot to a projectile-like blow at a point intermediate its ends and of sufficient force and magnitude to project the body laterally at a velocity approximately equal to the velocity of the blow-striking implement.

5. An apparatus for removing excess galvanizing material from an article coated by the hot dip process, comprising means for suspending the article from one end so that it is free to swing, a striker, of a mass comparable with that of the article, secured to a

relatively long, pivotally mounted rod, and means for moving the rod about its pivot point to impel the striker into contact with the article at a projectile-like velocity.

6. An apparatus for removing excess galvanizing material from articles coated by the hot dip process, comprising means for suspending the coated article from one end, so that the other end is free, a striker of a mass comparable with the mass of the article, a relatively long pivotally mounted rod on which the striker is mounted, and a pedal actuated motion multiplying device for swinging said rod about its pivot point.

In testimony whereof, I have hereunto subscribed my name this 9th day of March, 1920.

CHARLES L. PEIRCE, JR.
